UNITED STATES PATENT OFFICE.

CHARLES W. SMITH, OF PHILADELPHIA, PENNSYLVANIA, ASSIGNOR TO KEYSTONE TYPE FOUNDRY COMPANY, OF PHILADELPHIA, PENNSYLVANIA, A CORPORATION OF PENNSYLVANIA.

INKING MECHANISM FOR PRINTING-PRESSES.

1,326,537.

Specification of Letters Patent. Patented Dec. 30, 1919.

Application filed June 16, 1919. Serial No. 304,379.

To all whom it may concern:

Be it known that I, CHARLES W. SMITH, a citizen of the United States, residing at Philadelphia, in the county of Philadelphia and State of Pennsylvania, have invented 5 certain new and useful Improvements in Inking Mechanism for Printing-PresSES, of which the following is a specification.

One object of my invention is to provide 10 improved inking mechanism for printing presses, including a movable inking plate for conveying the ink to the form-inking rolls, and which will be operative to evenly distribute the ink upon the inking plate.

15 Another object is to provide improved means which will prevent the application of ink to the inking plate when there is no impression during the operation of the press, such for example as when the operator does 20 not insert a sheet of paper to be printed, and so that there will be no accumulation of ink upon the inking plate which is not necessary to form a proper impression.

25 A further object is to make the parts of my invention of a simple and durable construction.

These objects, and other advantageous 30 ends which will be described hereinafter, I attain in the following manner, reference being had to the accompanying drawings in which—

Figure 1 is a side elevation of a part of a printing press, such for example as the printing press shown in my co-pending 35 United States application, Serial Number 302,433, filed June 7, 1919, illustrating my improved inking mechanism,

Fig. 2 is a fragmentary plan view of a 40 part of the press shown in Fig. 1, and illustrating my improved inking mechanism, said figure being drawn on an enlarged scale from that shown in Fig. 1,

Fig. 3 is a fragmentary elevation of one end of Fig. 2,

45 Fig. 4 is a fragmentary elevation of the opposite end of Fig. 2,

Fig. 5 is a fragmentary plan view showing certain of the elements of my present invention,

50 Fig. 6 is a section taken on the line 6—6 of Fig. 5,

Fig. 7 is a section taken on the line 7—7 of Fig. 5, and

Fig. 8 is a section taken on the line 8—8

of Fig. 6 showing, in addition, a part of the 55 supporting structure.

Referring to the drawings, 9 represents a cylinder to which sheets of paper are attached, said cylinder having an oscillatory movement for conveying sheets to the printing-form 10, said printing-form forming a part of a carriage 11, said carriage also including an inking plate 12 adapted to engage, during a horizontal reciprocating movement of the carriage, the form-rollers 13 which are mounted on the frame 14 in suitable adjustable supports 15. The parts above mentioned may be of any suitable construction or design and do not by themselves 60 form a part of my present invention.

The frame 14 includes at one end an ink fountain 16 in which is rotatably mounted a fountain roll 17. This fountain roll is positioned within the ink within the fountain 16. A shaft 18 is journaled within the 75 frame 14 and has two arms 19 secured thereto. These arms at their outer ends form a rotatable support for a duct roll 20. The shaft 18 has a lever 21 secured thereto, said lever being connected by a link 22 with any 80 suitable means for imparting a rocking movement to the shaft 18, said means being illustrated as a cam 23 secured to a rotatable shaft 24, said cam being operative on a roller 25 on the link 22. The link 22 has a forked 85 end 22^a embracing and being supported by the shaft 24. The cam 23 acts to move the link 22 through the medium of the roller 25 and thereby causes the shaft 18 to be rocked to raise the duct roll 20. A continued movement of the cam 23 will permit the duct roll 90 to fall into engagement with the fountain roll 17 so as to take ink therefrom and apply it to the upper surface of the inking plate 12 when the plate 12 moves thereunder during 95 the reciprocation of the carriage 11 and after the arms 19 have been raised by the cam 23.

The frame 14 has adjustable supports 26 thereon and these supports form bearings for the shafts 27, 28 and 29 of ink distributing rolls 30, 31 and 32, said rolls being arranged in a row as clearly illustrated, and serving in a manner hereinafter described to evenly distribute the ink which has been applied by the duct roll 20, over the upper surface of the inking plate 12. All of the rolls 30, 31 and 32 are adapted to rotate due to the engagement of said inking plate, and the rolls 100 105

30 and 32 also have a longitudinal movement imparted to them so as to spread the ink over the width of the inking plate 12, said longitudinal movement being imparted by the elements now to be described.

A bracket 33 is secured to the frame 14 and provides a pivot for a lever 34. The lever 34 has two trunnions 35 and 36 at its opposite ends, said trunnions being disposed at opposite sides of the pivotal axis of the lever 34, as clearly shown in Figs. 2 and 5. The carriage 11 has an angular cam portion 37 which is adapted to engage a roller 38 on one end of the lever 34. A rod 39 has a spring 40 thereon which is backed against the frame 14, said spring serving to move the roller 38 into the path of movement of the cam 37, and it will be readily understood that during the reciprocation of the carriage 11, the cam 37 will swing the lever 34 in one direction and when the roller 38 is released from the cam 37, for example when the carriage 11 moves in an opposite direction, the spring 40 will swing the lever 34 in a direction opposite to the movement imparted to said lever 34 by the cam 37. The trunnions 35 and 36 are interposed between the flanges 41 and 42 of collars 43 and 44 respectively on the rolls 30 and 32. It will thus be noted that the above described swinging movement of the lever 34 will impart a longitudinal reciprocating movement to the rolls 30 and 32 so as to distribute the ink in the direction of the width of the inking plate 12. Furthermore, the rolls 30 and 32 will be moved in opposite directions at the same time, for example when the roll 30 is moving toward the right, as viewed from Fig. 2, the roll 32 will be moved toward the left, and alternately, when the roll 30 is moved toward the left the roll 32 will be moved toward the right. By this arrangement the ink will be moved simultaneously toward opposite side edges of the inking plate and the central roll 31 will merely rotate. In this manner, the ink is distributed evenly over all portions of the inking plate so that when the plate moves into engagement with the form-rolls 13, the latter will receive ink therefrom, and the ink will be evenly spread over the surface of the form-rolls to be applied to the form as it passes thereunder on its way to impart an impression to the paper upon the cylinder 9.

For the purpose of preventing the application of ink to the inking plate 12, if the operator for any purpose whatever fails to feed paper to the cylinder 9, I provide a swinging detent or stop 45 on the shaft 46 of the fountain roll 17. This detent 45 is weighted at 47 at its bottom below the shaft 46 so that normally it will swing its top end 48 into the path of the arms 19 during their downward movement so as to

stop the falling movement of the arms 19 before the duct roll 20 has had a chance to engage the fountain roll 17 and thereby prevent the duct roll 20 from receiving ink from the fountain roll. In this manner the inking plate 12 is prevented from receiving an excess amount of ink and the impression or printing will be uniform on all the sheets printed. During the normal operation of the machine, however, the detent 45 is swung out of the path of movement of the arms 19 by the hooked end 49 of a link 50, said hooked end being adapted to engage a pin 56 on the bottom of the detent 45, this action being clearly illustrated as starting to take place in Fig. 4. The link 50 is pivotally connected to an arm 51 which is attached to a plate 52. A number of fingers 53 are secured to a rock-shaft 54, said rock-shaft having an arm 55 thereon, the arm being provided with a pin 56 adapted to be engaged by the cam 57. The cam 57 is adapted to be rocked by a link lever 58 to cause said fingers 53 to be moved into and out of recesses 59 in a feed table 60. The shaft 54 has a screw threaded post 61 thereon adapted to engage a plate 62, said plate being secured to a pawl 63. The plate 52 has a small cam 64 thereon which provides a shoulder 65 for engagement with the pawl 63, said pawl being pivotally mounted on a fixed shaft 66 and serving to prevent the movement of said plate and the arm 51.

During the normal operation of the press, when the operator inserts the sheets between the fingers 53 and the recesses 59, the fingers 53 will be prevented from entering the recesses 59 and the pawl 63 will be held up out of engagement with the shoulder 65 so that the plate 52 and arm 51 will receive a swinging movement and thereby cause the hooked end 49 of the link 50 to swing the detent 45 out of the path of the arms 19 and permit the duct roll 20 to engage the fountain roll, to supply the necessary amount of ink to the inking plate 12 to permit the proper impression to be made. However, if the operator fails to insert a sheet between the fingers 53 and the recesses 59, the fingers 53 will move into the recesses 59, which movement will permit the pawl 63 to fall behind the shoulder 65 so that the plate 52, arm 51 and link 50 will be prevented from moving, and the detent 45 will swing by gravity into a position so as to prevent the arms 19 from dropping and thereby serving to prevent the duct roll 20 from engaging the fountain roll 17. In this manner no excess ink will be supplied to the inking plate 12 when there is no sheet to be printed. This action prevents the accumulation of ink upon the printing-form so that all impressions are similar.

It will be understood that while I have

described specific means for causing the link 50 to be moved during the normal operation of the press and permitted to remain inoperative when no sheet is fed to the 5 press, that any suitable means can be employed for moving or not moving the link 50 as above described.

While I have described my invention as taking a particular form, it will be understood 10 that the various parts of my invention may be changed without departing from the spirit thereof, and hence I do not limit myself to the precise construction set forth, but consider that I am at liberty to make 15 such changes and alterations as fairly come within the scope of the appended claims.

Having thus described my invention, what I claim as new and desire to secure by Letters Patent is:—

20 1. The combination of a movable inking plate; ink distributing rolls for engagement with said plate; a swinging lever pivoted between its ends; trunnions on said lever at opposite sides of the pivot, said 25 rolls having portions which said trunnions respectively engage; a roller on said swinging lever; a cam movable in conjunction with said plate and for engagement with said roller to swing the lever in one direction; and a spring for swinging said lever in the opposite direction when said cam moves away from said roller; substantially 30 as described.

2. The combination in a printing press of 35 a movable inking plate; an ink fountain roll; a duct roll; means for moving said duct roll into engagement with said fountain roll to secure ink therefrom and for moving said duct roll into the path of said 40 plate to apply said ink thereto; a pivoted detent adapted to swing into the path of movement of the duct-roll-moving means at each cycle of operation of the press; means operative during the printing action of the 45 press to swing said detent out of the path of said duct roll moving means; and means for rendering inoperative said detent moving means at other times to cause the latter to form a stop for said duct roll moving 50 means to prevent said duct roll from engaging said fountain roll; substantially as described.

3. The combination in a printing press of a movable inking plate; an ink fountain roll; a duct roll; means for moving said duct roll into engagement with said fountain roll to secure ink therefrom and for moving said duct roll into the path of said plate to apply said ink thereto; a pivoted detent; a hooked member; means for moving 60 said hooked member into engagement with said detent to move said detent out of the path of said duct roll moving means during each printing action of said press; and means for rendering inoperative said hooked 65 member at other times, whereby said detent forms a stop for the duct roll moving means to prevent said duct roll from engaging said fountain roll; substantially as described.

4. The combination with a printing press embodying an ink fountain and duct roll, of a detent normally holding the duct roll out of engagement with the ink fountain; a member adapted when actuated to move 75 the detent at each cycle of operation of the press; and means controlled by a sheet of paper in feeding position on the press to actuate said member.

5. The combination with a printing press 80 embodying an ink fountain and a form; of means to convey ink from the fountain to the form; means normally withholding such conveyer from action, and means controlled from a sheet in feeding position on 85 the press to withdraw the holding means.

6. The combination with a printing press embodying an ink fountain, a form, and a duct roll; a means to swing the duct roll upon a pivot into engagement with the ink 90 fountain at one limit of its movement; means normally withholding such duct roll from engagement with the ink fountain; and means controlled from a sheet in feeding position on the press to withdraw the holding 95 means.

In testimony whereof I have signed my name to this specification in the presence of two subscribing witnesses.

CHARLES W. SMITH.
